UNITED STATES PATENT OFFICE.

MILTON A. FESLER, OF OAKLAND, CALIFORNIA, ASSIGNOR TO FESS SYSTEM CO., OF SAN FRANCISCO, CALIFORNIA, A CORPORATION OF CALIFORNIA.

CENTRIFUGAL OIL-BURNER.

1,236,073.

Specification of Letters Patent. Patented Aug. 7, 1917.

Substitute for application Serial No. 853,597, filed July 28, 1914. This application filed June 14, 1916.
Serial No. 103,634.

To all whom it may concern:

Be it known that I, MILTON A. FESLER, a citizen of the United States, residing at Oakland, in the county of Alameda and 5 State of California, have invented new and useful Improvements in Centrifugal Oil-Burners, of which the following is a specification.

This invention relates to oil burners of 10 the type shown in my previous patent, #1,026,663, dated May 21, 1912, in which the oil is distributed centrifugally at the point of combustion and mixed with an annular stream of air issuing from the 15 burner.

One object of the present invention is to operate the oil distributer means through the medium of a blast of air which furnishes the necessary draft. Another object is to so 20 feed the oil to the distributer that there will be an equitable distribution maintained at all times with a minimum flow of oil. Another object is to provide means for delivering air for combustion, both above and below 25 the issuing oil film, so that the oil issues between upper and lower layers of air. A further object is to provide for regulating the volume of air in proportion to the fuel consumption. There are other objects and 30 advantages which will be apparent hereinafter.

The invention consists of the parts and the construction and combination of parts as hereinafter more fully described and 35 claimed, having reference to the accompanying drawings, in which—

Figure 1 is a vertical section of the invention taken on line 1—1 of Fig. 2.

Fig. 2 is a plan view, in section, taken on 40 line 2—2 of Fig. 1.

Fig. 3 is a section taken on line 3—3 of Fig. 1.

Fig. 4 is a detail, in side elevation, of the oil discharge cap.

45 Fig. 5 is a plan view of parts of Fig. 4, taken on line 5—5 of Fig. 1.

A represents the burner casing or shell, which is here shown in the form of an elbow, with a lateral air intake 2 of considerable 50 dimensions. Suitably supported vertically within the casing is an oil feed pipe

3, surmounted at its upper end by the burner head 4, which is suitably insulated against the intense heat of the fire-box, to which the device is designed to be placed.

Surrounding the pipe 3 is a revoluble sleeve 5, turning in suitable anti-friction bearings 6 in the air draft passageway 7 within the burner casing. Sleeve 5 carries the oil distributer 8, which consists of a hub 60 portion 9, having an annular trough 10, with spokes 11 and the outside rim or saucer portion provided with the equalizing distributer grooves 12 and 13; the rim or lip of the distributer 8 extending into the passageway formed between the periphery of the head 4 and removable ring 14 constituting the upward extension of the casing A.

Sleeve 5 and the oil distributer 8 are rotated through the medium of a blast of air 70 entering at 2 from any suitable source of supply and with the desired velocity, reacting on the fan 15 which is mounted on sleeve 5 in passageway 7. By this construction the air blast for effecting combustion 75 is utilized as a motive power to operate the oil distributer. This greatly simplifies construction.

The oil for combustion is delivered into the trough 10 from the pipe 3 through perforations 16, Fig. 5, between the two caps 17 and 18; the caps 17 and 18 fitting one over the other and around the pipe 3 a suitable space from one another and suitably supported on a ledge or a shoulder 19 85 on the pipe 3.

The distributing caps, 17, 18, are cut on the bevel as shown in Fig. 4, so that the oil issuing from pipe 3 through perforations 16, will flow down between the caps 17, 18 and 90 discharge in uniform flow at the lowest point into the trough 10 of the rotating oil distributer, irrespective of the quantity of oil fed to the burner, thus by a uniform delivery of oil at one side of the trough, and 95 the trough having a rim with the narrowest diameter of the trough at the rim, the oil will, by centrifugal action, distribute itself entirely around the trough until the latter is filled, whereupon there will be a constant annular film of oil overflowing the trough.

This is quite an important feature where it is desired to use only a small amount of oil at any time.

The trough 10 has its vertical wall concaved, as shown, so that the oil fed into the trough from the feed caps 17, 18, banks up against this vertical wall and then gradually overflows the rim 20 into the ports 21 in spokes 11, spokes 11 being suitably spaced 10 so as to allow the air to pass up from the passageway 7 into the space 22 above the oil distributor.

The oil as it issues from the passage 21 and hollow spokes strikes against the wall 15 of the groove 12, there again to bank up and distribute around the circumference of the burner, overflowing in a thin film as the groove fills into the second groove 13, where equitable circumferential distribution is 20 further effected; the oil finally flowing in an even thin film over the entire distributing rim or lip of the distributor 8; simultaneously a volume of air which is being continuously forced through the burner is 25 divided, and part of it passes out through the space 25 on the under side of the distributor and part of it passes between the spokes into the space 22 and out through the annular space 26 above the oil distributor.

30 In order to regulate the volume of air in proportion to the amount of fuel used and effect perfect combustion at all times, I employ a means for bypassing such quantity of the air as is not needed. To this end I employ a damper ring 27, fitting around the burner ring 14, the latter having ports 28 at intervals adapted to register with one or the other sets of ports 29-30 in the distributor ring 27. The ports 29 open directly 40 to atmosphere, while ports 30 open into flues 31, having their outlet adjacent to the upper edge of the burner ring 14 and in proximity to the annular discharge orifices 25, 26. The damper ring 27 is operated at 45 any suitable point by appropriate connections represented at 32, Fig. 3.

When the burner is working on low fire the damper ring 27, is turned to bring the ports 28, 29 more or less into register according to the amount of air that is required to maintain combustion; this quantity being delivered through the passages 25, 26. As more oil is turned on more air is 50 needed for combustion resulting in shifting the damper 27, so that eventually ports 29 may be closed and the flue ports 30, 28, brought into register and the entire air capacity of the burner will be delivered up 55 into the fire box in immediate proximity with the combusting gases, this air supply 60 issuing through ports 31 in addition to the regular discharge orifices 25, 26.

In order to light a burner of this sort, I provide a pilot burner 35, suitably attached 65 to the top of the burner casing adjacent to

head 4 and out of interference with the damper 27, to which pilot, gas may be supplied from any suitable source. When it is desired to light up, this gas pilot is first ignited, then the oil is turned on and the air 70 blast started, whereupon the burner is quickly lighted without the use of paper or other charry material, which has the disadvantage of clogging up the burner at the point of discharge. As soon as the burner 75 is lighted the pilot is turned off.

The bypassing of the air, it is to be noted, takes place between the fan and the burner tip, so that the action of the fan will not be interfered with. Manifestly if the volume of air to the burner should be decreased or otherwise varied at a point outside the burner or before reaching the fan, it would interfere with the oil distributing apparatus.

Having thus described my invention, what I claim and desire to secure by Letters Patent is—

1. A centrifugal oil burner having means for the circumferential distribution of an 90 annular oil stream, means for supplying a blast of air above and below said oil stream, means operated by said blast of air to rotate said oil distributing means, and means to vary the volume of air delivered to said oil 95 stream without varying the speed of the oil distributing means.

2. In a centrifugal oil burner, a centrifugal atomizing cup adapted to discharge an annular oil stream, means for supplying an 100 air blast above and below said oil stream, a fan operated by said air blast adapted to rotate the atomizing cup and means for bypassing a portion of the air after it has passed through the fan to vary the column 105 of air delivered to the oil stream.

3. In a revolving oil burner, a centrifugal atomizing cup provided with an annular discharging lip, means for delivering oil to the cup and a plurality of super-posed annular 110 ridges formed interiorly of the cup to cause an even distribution of the oil delivered to the cup before the oil discharges therefrom by centrifugal action.

4. A centrifugal oil burner comprising a 115 casing, an oil delivery pipe therein, an air passageway surrounding said pipe, a centrifugal oil distributor mounted on said pipe, and a discharging means from the pipe to the distributor comprising a pair of spaced 120 caps projecting downwardly and cut on the bevel substantially as described.

5. An oil burner comprising a fixed vertical oil feed pipe, an oil distributor mounted for rotation on said pipe and having a hub 125 portion, a trough having a rim overflow with the overflow rim of the trough of less diameter than the portion of the trough below the rim formed in said hub portion and into which trough said oil pipe discharges, hol- 130

- low spokes with their inner ends opening to the trough, and an outside annular rim, the oil being adapted to flow under the action of centrifugal force from said trough through 5 the hollow spokes onto said annular rim.
6. An oil distributer comprising a rotary member having a hub portion with a trough formed in said hub portion, said trough having an outer vertical concaved wall to 10 provide an overflow rim of less diameter than the portion of the trough below the rim, hollow spokes, and an outside annular rim, the oil being adapted to flow under the action of centrifugal force from said trough 15 through the hollow spokes on to said annular rim.
7. An oil distributer comprising a rotary member having a hub portion with a trough formed in said hub portion, said trough having an outwardly concaved outer wall with a 20 rim overflow, hollow spokes, and an outside annular rim, the oil being adapted to flow under the action of centrifugal force from said trough through the hollow spokes on to 25 said annular rim, said rim portion having an inclined wall with one or more circumferential concaved portions therein forming grooves for effecting a circumferential distribution of the oil, substantially as de- 30 scribed.
8. A centrifugal oil burner and oil distributer having a circumferential annular discharging lip and having an inclined wall with a plurality of super-posed circumferential concaved portions therein forming 35 grooves for effecting a circumferential distribution of the oil.
9. An oil burner comprising a casing having an air passageway formed therein, a 40 vertical oil delivery pipe extending through said passageway, a sleeve rotatable on said oil pipe, a fan on the sleeve rotatable by the air blast through said air passageway, a rotary oil distributer having hollow spokes
- mounted on the sleeve, and a burner head, 45 the oil distributer forming with the walls of the casing and with the burner head upper and lower discharge passageways connected with the said air passageway.
10. A centrifugal oil burner having means 50 for the circumferential distribution of an annular oil stream, means for supplying a blast of air in conjunction with said oil stream, and means operated by said blast of air to rotate said oil distributing means, 55 and means to vary said blast of air delivered in conjunction with the oil stream to effect combustion without varying the speed of rotation of the oil distributing means.
11. An oil burner comprising a fixed vertical oil feed pipe, an oil distributer mounted for rotation on said pipe and having a hub portion, a trough having a rim overflow with the overflow rim of the trough of less diameter than the portion of the trough 60 below the rim formed in said hub portion and into which trough said oil pipe discharges, hollow spokes with their inner ends opening to the trough, and an outside annular rim, the oil being adapted to flow under 65 the action of centrifugal force from said trough through the hollow spokes on to said annular rim, said outside annular rim having an annular baffle groove in the path of the discharge from said spokes and into 70 which groove the fluid from said spokes discharges, said groove having its outer wall concaved to provide an overflow lip of less diameter than the portion of the groove below said overflow lip. 75
- In testimony whereof I have hereunto set my hand in the presence of two subscribing witnesses.
